[57] CLAIM

The ornamental design for an enclosure for portable voltage conditioning equipment and the like, as shown.

DESCRIPTION

FIG. 1 is a perspective view of the enclosure for portable voltage conditioning equipment and the like showing our new design;

FIG. 2 is a top plan view thereof;

FIG. 3 is a front elevation thereof;

FIG. 4 is a right side elevation thereof;

FIG. 5 is a rear elevation thereof;

FIG. 6 is a left side elevation thereof;

FIG. 7 is a bottom view thereof.
